UNITED STATES PATENT OFFICE.

WILFRED KOYEN AND OLE CHRISTIAN ERICKSON, OF DETROIT HARBOR, WISCONSIN.

HEN'S NEST.

1,141,346.

Specification of Letters Patent. Patented June 1, 1915.

Application filed June 25, 1914. Serial No. 847,243.

To all whom it may concern:

Be it known that we, WILFRED KOYEN and OLE C. ERICKSON, citizens of the United States, residing at Detroit Harbor, in the county of Door and State of Wisconsin, have invented certain new and useful Improvements in Hens' Nests; and we do declare the following to be a full, clear, and exact description of the invention, such as will enable others skilled in the art to which it appertains to make and use the same.

This invention relates to new and useful improvements in nests for poultry and more particularly to a hen nest and the primary object of the invention is to provide a device of this character with means for trapping the eggs.

A further object of the invention resides in providing a nest having an opening in the bottom thereof leading to a trap or other receptacle for receiving the eggs as the same are laid, thus preventing the same from being eaten by the hen and also preventing the soiling thereof.

Still another object of the invention resides in providing a device which is simple and durable in construction, inexpensive to manufacture and one which will be very efficient in use.

With these and other objects in view our invention consists in the novel features of construction, combination and arrangement of parts as will be hereinafter referred to and more particularly pointed out in the specification and claims.

In the accompanying drawings forming a part of this application: Figure 1 is a side elevation of a device constructed in accordance with our invention and applied to use; Fig. 2 is a vertical section therethrough; Fig. 3 is a front elevation of the same; Fig. 4 is a bottom plan view thereof; Fig. 5 is a detail elevation of the means for securing the rings or coils of the wire to the bracing strip; Fig. 6 is a vertical section through the last mentioned securing means; Fig. 7 is a front elevation of a slightly modified form of the invention; and, Fig. 8 is an end elevation of the same.

In describing the invention we shall refer to the drawings in which similar reference characters designate corresponding parts throughout the several views and in which 1 indicates a bowl-shaped frame the latter consisting of a large upper ring 2 and a lower small ring 3 the same being connected

by the arcuate strips 4. Also connecting these strips 4 between the large upper ring 2 and the small lower ring 3 are the coils 5 of a spiral wire member which extends 60 from the lower ring 2 to the upper ring 3, thus completing the bowl-shaped design of the frame. This bowl-shaped frame is lined with a straw lining 6 which is secured to the rings and strips in any desired manner 65 and continues from the upper ring 2 to the lower small ring 3. This frame, lined as shown and described, forms the nest proper and in view of the small ring 3 at which point the lining terminates it will be seen 70 that a central opening is provided in the nest, the purpose of which will be herein-after and more particularly set forth.

It is a well known fact that in nests which are usually used for poultry wherein no 75 openings are provided in the bottom thereof, hens are apt to eat the eggs and furthermore by permitting the eggs to remain in the nest proper for any length of time the same will obviously become soiled, which is undesirable when the eggs are to be packed and shipped for commercial purposes. It is also a fact that when eggs are permitted to remain in the nest for even a short time the hen is liable to heat the same by setting 80 thereon and thus injure the same for commercial purposes.

Our invention primarily contemplates the provision of means for trapping the eggs immediately after the same are laid in the 90 nest and in carrying out this idea we provide a bowl-shaped nest having a central opening in the bottom thereof as above described and shown in the drawings. In this manner as soon as the egg is laid the same 95 rolls to the central opening and passes therethrough and we have also provided a trap or other receptacle for receiving the egg from which point the same may be readily removed by the caretaker.

The trap which we have provided for a single nest consists of a tray or the like 7 which is formed of a frame 8 covered by wire mesh or the like 9. This frame 8 is preferably of heavy wire and portions thereof are continued upwardly to form the supporting or attaching arms 10. The space between these arms is also covered by a wire mesh which forms the rear wall of the tray.

The wire forming the frame of the tray 110 is connected at the front end of the tray to portions of the frame 1 of the nest at points

adjacent the central opening therein and the upper ends of the arms 10 are also removably attached to the upper ring 2 of the frame 1. The attachment of the forward 5 end of the tray or trap to the lower portion of the frame is such, however, that the rear wall of the tray or trap is disposed slightly beyond the wall of the frame so that in order to secure the upper ends of the arm 10 to the ring 2 said arms are offset somewhat as shown at 11. The ring 2 at points between the engagement of the arms 10 on said ring is looped to form the eyes 12 and these eyes afford means whereby the complete device may be attached to the wall of a 15 structure.

In view of the fact that the rear wall of the trap or tray 7 is disposed slightly beyond the wall of the frame it will be appreciated that in the securing of the device against the wall of a structure, the same will be slightly inclined in an upward direction toward its forward end. In this manner the eggs which are passed from the opening in 25 the nest proper to the trap or tray therebelow will be directed rearwardly against the rear wall of said tray or trap to be readily removed therefrom.

It must be here stated that the side and 30 front walls of the tray or trap are lower than the rear wall thereof as is clearly seen in the side elevation of the device shown in Figs. 2 and 3 of the drawings. It will also be seen from the drawings that by so constructing the trap or tray and so disposing the same with respect to the nest proper as above mentioned, spaces are provided between the tray or trap and the nest proper whereby to readily admit the hand of the 35 caretaker. In this manner the eggs within the tray or trap may be readily removed when desired.

The description above refers to a single nest but we have also provided construction 45 for a plurality of nests attached one to the other and in Figs. 7 and 8 we have shown such a construction. In these figures we have shown a pair of nests 13 and 14 which are constructed the same as the nest above referred to, each being bowl-shaped and having a central opening 15 in the bottom thereof. These bowl-shaped nests 13 and 14 are applied in abutting relation to one another and are held in such position by means of 50 the receptacle or the like 16 which forms the trap proper. This receptacle is of somewhat bowl-shaped design and conforms to the outline of the bowl-shaped nests 13 and 14 at the front and rear portions of the latter, said receptacle or trap being constructed of 55 an outer frame covered by wire mesh or the like similar to the trap or tray 7 referred to hereabove.

It will be seen that as the eggs are laid in 60 the nests 13 and 14 the same will pass

through the openings 15 thereof to the receptacle 16 therebelow and roll to the center of the latter point the receptacle or trap 16 is provided with an opening covered by a screen door 17 whereby the eggs therein may be readily removed when desired. In order to secure this kind of nest to a structure, the arms 18 are provided at the rear portions of the nest to extend upwardly and afford means for readily applying a securing means to support the complete device on a wall or other structure. Of course, while we have shown but a pair of nests in this form of the device it will be understood that as many nests may be provided as are found desirable for use in connection with a single trap or receptacle for receiving the eggs passed through the openings in said nests.

From the foregoing it will be seen that we have provided a simple, inexpensive and efficient means for carrying out the objects of the invention and while we have particularly described the elements best adapted to perform the functions set forth it is obvious that various changes in form, proportion and in the minor details of construction may be resorted to, within the scope of the appended claims, without departing from the spirit or sacrificing any of the principles of the invention.

Having thus described our invention, what we claim is:

1. A nest of the class described comprising a bowl-shaped frame having a central opening in the bottom thereof, a lining for the frame, a receptacle to receive eggs passed through the opening in the latter, said frame secured at adjacent points on its upper edge to the wall of a structure, and supporting means depending from the upper and lower edges of the frame to carry said receptacle, with an offset portion to hold the frame and receptacle in a slightly upwardly inclined position from the structure wall to carry the eggs to the rear of said receptacle.

2. In a nest of the class described, a bowl-shaped frame having an opening in the bottom thereof and secured at its upper edge to the wall of a structure, a lining therefor, a receptacle having its forward end held beneath the lower portion of the frame adjacent the opening therein, and said receptacle projecting laterally toward the said structure, and two supporting wires for said receptacle having their forward ends secured to said frame adjacent the opening therein, and their rear ends secured to the upper edge of the frame at points on either side of the adjacent fasteners to the structure wall, said supporting wires having an offset portion for holding said frame and receptacle slightly inclined upward from said wall.

3. In a nest of the class described, a bowl-

- shaped frame having an opening in the bottom thereof and secured at its upper edge to the wall of a structure, supporting wires secured to the upper and lower edges of said frame and depending therefrom, a receptacle supported by said wires having its forward end held beneath the opening in said frame and projecting rearwardly toward the said structure and the supporting wires depending from the upper edge of the frame being offset to project against the structure wall, thereby holding said frame and receptacle in a slightly inclined upward position upon said wall to carry the eggs dropped in said receptacle to the rear.
4. In a nest of the class described, a bowl-shaped frame comprising upper and lower ring members, the former being of greater diameter than the latter, arcuate connecting strips therebetween, said strips being each

provided with spring locking tongues and a spirally designed wire member connected at its ends with said ring members and circumscribing said strips, the coils of said wire member being engaged with the locking 25 tongues of said strips, a lining for the frame extending from the upper to the lower ring member and leaving an opening in the bottom of the frame, and a receptacle carried by the frame to receive eggs passed 30 through the opening in the latter.

In testimony whereof we have hereunto set our hands in presence of two subscribing witnesses.

WILFRED KOYEN.
OLE CHRISTIAN ERICKSON.
